COKING PROCESS

Walter F. Rollman, Cranford, N. J., assignor to
 Standard Oil Development Company, a corpora-
 tion of Delaware

Application February 18, 1941, Serial No. 379,397

7 Claims. (Cl. 202—8)

The present invention relates to improvements in the art of treating hydrocarbon oils and, more particularly it relates to a method of coking heavy residual petroleum oils, such as topped or reduced crude petroleum oils, to secure quantities of hydrocarbons boiling within the gas oil range, together with some gasoline, normally gaseous hydrocarbons and coke.

A great deal of research and experimentation has been carried out by the oil industry directed toward improving coking operations. Heretofore, and in many instances at the present time, after a crude petroleum oil has been topped to remove by distillation constituents boiling up to say 825° F.—850° F., the residual oil, often called "reduced crude," is subjected to a pyrolytic treatment such as coking or viscosity reducing in order to obtain additional quantities of gas oil, that is, hydrocarbon oils boiling within the range of say from 400° F.—850° F., which gas oil may be used as a charging stock for a thermal or, preferably, catalytic cracking operation to produce a gasoline of high octane number. In so far as the coking operation is concerned, the practice has been to preheat the oil to coking temperatures in say a tube furnace and thereafter to discharge the preheated oil into a coking retort or drum, preferably heat insulated, in which drum the oil undergoes conversion to form gas oil, gasoline and other products including coke. In such an operation, the coke formed unavoidably deposits as a solid clinging to the bottom and side walls of the drum, which is eventually nearly filled so that periodically the operation must be discontinued to remove the coke. The first step in decoking a drum of the kind referred to above is to discontinue the oil feed and permit the drum to stand for a time, say 24 hours, for the purpose of drying and hardening the contained coke. At the end of this time hydrocarbon vapors are displaced out of the coking drum by means of steam, the drum is cooled with water, opened, and the coke removed. There are several methods in use for the removal of coke from the coking drum, namely, pulling out a cable which was strung spider-web fashion in the drum prior to the operation; drilling and knocking out the coke with a kind of revolving hammer; or removing the coke by means of very high pressure streams of water emitted from a revolving nozzle head pushed through a hole drilled in the coke. The decoking of a drum is, therefore, a laborious and time-consuming operation when practiced intermittently as indicated above. It also requires additional equipment, because the usual practice is to employ two or more drums of which drums one or more is in on-

stream operation while the other or others are being decoked.

The present invention is directed toward a process for coking continuously and broadly contemplates so manipulating the coking operation as to cause the formation of a hard, dry, free-flowing granular coke which is non-adherent and which therefore may be continuously removed from the coking drum thus obviating the necessity of discontinuing the coking operation to remove large quantities of coke. I accomplish this result by providing a coking drum containing three distinct sections as follows: (1) a top feed introduction section operating slightly below normal coking temperatures into which section the oil is sprayed; (2) a coking section; and (3) a coke drying section maintained at a high temperature by the introduction of air and fuel gas.

The present invention will be best understood 20 by reference to the accompanying drawing in which Fig. I shows schematically a form and arrangement of apparatus elements in which the present invention may be carried into effect; and Fig. II shows an enlarged modification of the 25 equipment employed in discharging the oil into the coking drum. Throughout the several views similar reference characters refer to similar parts.

Referring in detail to the drawing, a heavy hydrocarbon topped crude oil or reduced crude is 30 discharged into the system through line 1 and thence discharged into a preheater 3, and thence discharged through line 5 into a coil 6 disposed in a furnace setting 8 where the oil is heated to a temperature of say 800° F.—950° F. The oil 35 thus heated in coil 6 is withdrawn from said coil through line 10 and discharged into a spray head 14 located in the upper section of a vertical coking drum 16 where the oil is formed into small droplets and thereafter discharged into the interior of said drum. The oil discharged into the drum is at a temperature such that it will not readily form coke on the inlet spray head but is thereafter heated to coking temperatures in a manner which will be presently explained. The 40 spray head is, as stated, employed to convert the oil stream into particles directed straight downwardly, in preference to a nozzle, because of the tendency of a nozzle to direct some of the oil against the wall and to produce some mist which would entrain out of the drum. The upper or feed zone is provided with a cooling jacket 20 through which is circulated water or any other suitable coolant for the purpose of keeping this feed zone, and, more particularly, the feed spray head at a temperature slightly below that at 45 which the oil feed will readily coke, thereby pre-

venting the accumulation of coke on the oil feed spray head. Any other suitable method may be employed to prevent overheating the spray head or oil in contact with it. For example, the inner wall of the feed zone may be covered with an insulating material to reduce radiation of heat from the walls in this section to the spray head; or the feed zone may be separated from the remainder of the coking drum by means of a heat insulating gasket to prevent the metallic conduction of heat through the walls to the feed zone. In any case, the feed zone section need be no longer than is necessary to thus insure that the spray head is not exposed to excessive temperatures.

The finely divided oil particles fall through a stripping and/or coking zone S heated to some extent by rising combustion gases formed in a manner which will subsequently be explained. Experience in the study of continuous coking has shown that if the oil is preheated substantially to coking temperature, and is finely divided, in a hot coking drum conversion to coke is completed very quickly and consequently the coking zone need not be excessively long, e. g., it may be say 25 to 100 feet. However, it is not necessary to produce an absolutely dry coke in the coking zone, and consequently the small quantity of tacky material remaining after the initial rapid flashing and cracking, which produces very little useful products and is the most refractory fraction of the charging material, need not be completely coked in the coking zone. This is an important advantage in that it materially shortens the length of the coking zone required. Oil vapors and some combustion gases are taken off at the top of the coking zone through line 26 and these may be conducted to fractionating equipment to separate and recover desired fractions. If the oil is discharged into the drum in the manner indicated above very little, if any, oil is entrained in the vapors discharging through line 26. The falling coke particles in coking section S, which may still be tacky, pass from the coking zone through the drying zone D where they are completely dried and, if desired, partially burned to produce heat which may be utilized in the operation in section S. The drying zone D is maintained at a very high temperature, say 1050° F. to 1800° F., by the combustion of gas introduced through line 28 into a ring burner 30 located as shown near the bottom of the drying section, and since reaction takes place very quickly at these conditions, this section may be fairly short, say not more than 6 or 8 feet. The air necessary to support the combustion is introduced through line 32 into a perforated ring member 34 similar in construction to ring 30. The air and combustion gas discharged respectively into the coking drum through lines 32 and 28 may ordinarily be at room temperature. A supply of excess air over that required to consume the extraneous combustible gas is discharge through line 32 into the coking drum, the purpose of the excess air being to facilitate drying by burning off any tacky material which may remain on the coke particles at this point, and also for the purpose of burning some of the coke, which thus supplies part of the necessary heat of coking. Extraneous gas is used for combustion, as indicated, in preference to introducing air into the drum because the latter procedure would destroy valuable products of the coking process.

namely, normally gaseous hydrocarbons, and hydrocarbons in the gasoline and gas oil boiling range, and would also introduce an undesirable quantity of oxygenated bodies into these products. As a further precaution against getting excess oxygen into the coking zone extraneous gas is introduced through line 35 into perforated ring 36 located at or near the top of the drying section, which gas will be consumed by the excess oxygen that may remain in the drum at this point. However, it is known that the presence of some oxygen in the coking drum has the effect of increasing the octane number of the gasoline produced in the coking operation and consequently it may be preferable to permit some oxygen to enter the stripping and coking section, although obviously the amount of oxygen must be carefully controlled in this type of operation. Some of the hot gaseous products of combustion are permitted to rise through the coking zone where, as indicated, they serve to strip and heat the descending charging oil, but most of the combustion products are taken off through a collector ring 40 carrying a vent 45, thus reducing the quantity of fixed gases which must subsequently be handled by the fractionating equipment attached to the unit, and also reducing the tendency of oil and coke particles to entrain out of the coke drum because of excessive gas velocities in the stripping and coking section. The sensible heat of the combustion gases, however, may be used to heat the stripping section of the coking drum by passing them through a jacket (not shown) surrounding this section of the drum, but heat transmission from gases in a jacket of this type to falling particles in the drum is poor, and the slight advantage of the jacket does not usually warrant the expense of installing it. In any case, much of the sensible heat of the flue gases is recovered by heat exchangers with the oil feed by indirect contact and, consequently, only a small fired preheater coil 6 is required. If the coking process is so operated that the flue gases contain hydrocarbons, they may be burned by introducing air at or near the point where the gases enter the heat exchanger 3, that is to say through line 43, and the sensible heat thus released may be at least in part recovered in heat exchanger 3. The gases passed thru heat exchanger 3 may be withdrawn from the heat exchanger thru line 44.

Desirable lengths of the several sections of the coking drum have been considered above in the discussion of the respective sections. The relative order of increasing diameter of the three sections of the coking drum should be, (1) feed section, (2) stripping and coking section, and (3) drying section. The feed section should be as narrow as possible consistent with avoiding the contact of oil feed with the walls, to prevent hot vapors from the stripping section from sweeping up into the feed section and consequently overheating and causing the formation of coke on the feed spray head. The diameter of the stripping and coking section is such that the falling particles are not likely to deflect sufficiently to come into contact with the walls, and vapor velocities are not sufficient to entrain oil or coke particles out of the drum; yet the diameter of this section must not be so great that vapor contact time and consequently destructive cracking in this section is excessive. In order to avoid excessive turbulence and vapor velocities because of the comparatively large volume of gases present, the diameter of

the drying section is greater than that of the stripping and coking section.

It should be stated that for best operating conditions the pressure maintained throughout the coking drum is preferably low, say 5 lbs./sq. in. gauge, although the process is entirely feasible at higher pressures provided the coking drum temperature is high enough to insure rapid flashing and coking of the oil feed. Under the conditions stated, the coke formed in the process is in the form of hard, dry pellets or "buckshot" which is free-flowing, and this material collects in the bottom of the coking drum and may be withdrawn through star feeder 50 and delivered to storage.

Referring in detail to Figure II, the spray head consists as shown of a plurality of downwardly projecting nozzles 55 tapering to an orifice of, say, 5-15 mm. in diameter. In order to assist in the stripping and coking operation, and more particularly to facilitate the egress of the oil from the spray head uniformly in small droplets directed substantially straight down, superheated steam having a temperature of say 800° F.-900° F. is discharged into the spray device through line 56 in the manner shown.

To recapitulate, it may be observed that my process as described above may be operated continuously from day to day without necessitating frequent shutdowns to remove coke from the coking drum. The coking drum itself consists of three sections, namely, a feed section, a stripping section, and a coke drying section. As indicated, the feed stock is discharged into the upper section, namely, the feed section, at a temperature slightly below normal coking temperatures; and in order to prevent coking in the feed section, especially on the feed spray head, this section is maintained slightly below coking temperature by means of water or any other suitable coolant circulated through a cooling jacket. The additional heat required to cause rapid and complete coking of the oil particles is preferably supplied by burning a gas such as CO, hydrogen, hydrocarbon gases or the like, in the drying section. It is also preferable to cause some limited combustion of the coke produced in the lower part of the stripping section in order to further facilitate drying and coking of the partially coked particles. In some cases it is desirable to maintain an excess of oxygen in the drying section and permit part of it to escape to the coking section, since it has been found that small quantities of oxygen in the coking zone improve the octane level of the gasoline produced.

As for a range of conditions, the charging oil in line 10 should be at a temperature of from 800° F.-950° F. and discharged into the feed section at this temperature. The pressure maintained in the drum should be from atmospheric to 100 lbs./sq. in. gauge. The temperature in the drying section should be from 1050° F.-1800° F. for best results. Oil feed rate is limited only by the tendency of oil to entrain out of the coking drum or deflect to the sides.

Many modifications of my invention may be made without departing from the spirit thereof.

What I claim is:

1. A continuous process for coking heavy residual hydrocarbon oils which comprises preheating the oil to coking temperatures, atomizing the preheated oil into an elongated vertical coking zone, cooling said oil during said atomization to prevent premature coking, permitting the atomized oil so formed to descend through

a stripping and coking section, withdrawing a tacky coke from the said coking and stripping section, and discharging it into a drying section where it is heated by combustion gases to temperatures sufficiently high to cause the formation of hard, dry pellets of coke, recovering hydrocarbon vapors from the upper section of the coking zone and pelleted coke from the bottom of the coking section.

10 2. The process set forth in claim 1 in which the oil is preheated to a temperature within the range of from about 800° F. to 950° F., the temperature in the stripping and coking zone is from about 850° F. to 1200° F., the temperature in the drying zone is from about 1050° F. to 1800° F., the pressure in the coking drum is from 0 to 100 lbs./sq. in. gauge pressure and the feed rate of oil to the drum is determined by the tendency of the oil or coke particles to be entrained in the vapors egressing from the coking zone.

15 3. The process set forth in claim 1 in which the oil is preheated to about 825° F., the temperature in the coking and stripping zone is about 1000° F., the temperature in the drying zone is about 1400° F., the pressure in the coking zone is about 5 lbs./sq. in. gauge and the feed rate of oil to the coking zone is about 0.6 volume of cold oil per zone volume per hour.

20 4. The process set forth in claim 1 in which the drying section is heated by means of combustible gases.

25 5. In an apparatus for the coking of residual oil, a vertical shell having a feed inlet zone, a coking zone, and a coke-drying zone, cooling means in said feed inlet zone, means in said coking zone for removing oil vapors, means in the bottom of said drying zone for introducing a hot inert gas thereinto, means in the top of said drying zone for removing most of said introduced gas, means in the top of said coking zone for removing oil vapors and the remainder of said introduced gas, and means in the bottom of said shell for discharging dry coke.

30 6. An apparatus for coking oils comprising a vertical shell having a head at its upper end, a collector ring near its middle portion, and a drying and combustion zone at its lower end, means in said head for introducing oil to be coked, cooling means adjacent said oil-introducing means, means in said drying and combustion zone for passing a current of hot gas upwardly through said shell, means in said collector ring for removing most of said gases being passed through said shaft, means near the top of said shell for withdrawing oil vapors and the remainder of said gases passing upwardly through said shell, and means in the bottom of said shell for removing coke.

35 7. A coking tower for residual oils comprising a vertical tubular shell having a head at its upper end and an expanded section near the middle portion thereof, means in said head for introducing the oil to be coked, cooling means adjacent said oil-introducing means, an escape duct for volatile products communicating with the top of said shell, means below said expanded section for passing a current of hot gas upwardly through said shell, an escape duct in said expanded section for removing most of said hot gases, and means in the lower portion of said shell

40 for burning a portion of the coke formed so as to dry the remainder of said coke, and means for withdrawing dry coke from the bottom of said shell.
